VACUUM CLEANER

Salvatore Buda, Brooklyn, N.Y., assignor to Strapavac Corp., Brooklyn, N.Y., a corporation of New York

Filed Apr. 23, 1959, Ser. No. 55,629

Term of patent 14 years

(Cl. D9—2)

The figure is a perspective view of a vacuum cleaner embodying my new design.

The side, not shown, is substantially like the side shown and the end not shown is substantially plain.

I claim:

The ornamental design for a vacuum cleaner, as shown and described.
